UNITED STATES PATENT OFFICE.

PORFIRIO DIAZ, HIJO, OF MEXICO, MEXICO.

METHOD OF TREATING THE SOIL.

No. 901,078.

Specification of Letters Patent.

Patented Oct. 13, 1908.

Application filed April 15, 1908. Serial No. 427,239.

To all whom it may concern:

Be it known that I, PORFIRIO DIAZ, Hijo, a citizen of Mexico, resident of the city of Mexico, Republic of Mexico, have invented 5 certain new and useful Improvements in Methods of Treating the Soil, of which the following is a specification.

This invention comprehends certain new and useful improvements in methods or processes for treating the soil, and has for its object an improved process of this nature which consists in the utilization of electric currents of high tension and great frequency in order to effect the assimilation by the 15 plants of the atmospheric nitrogen or azote.

With this object in view, the invention consists in an improved method which I shall now describe in detail, reference being had, for a full understanding of the invention, to 20 the following description and accompanying drawing, in which latter one application of my invention is diagrammatically illustrated.

Figure 1 illustrates a field to be treated by 25 the process; Fig. 2, two of the poles, or masts employed; Fig. 3 a generator of Hertzian waves, and Fig. 4 the poles or electrodes of the generator and a parabolic reflector which is employed therewith.

In carrying out my invention and in order 30 to accomplish the object aimed at, I place an apparatus which produces the Hertzian waves *c* (Fig. 4), in the center of the field to be treated, or very near the center, upon any 35 suitable support or fulcrum. I also provide a parabolic reflector *b* (see Fig. 4), which may be moved along the support, and it is to be understood that the wave producer may be adjusted by means of any suitable mech- 40 anism (not shown) on the focus of the parabolic reflector; the distance of the principal foci of the reflector may be measured by means of a scale or vernier, as indicated in Fig. 4, for a purpose hereinafter described.

Around the wave producing point, and at 45 any desired intervals in the field, I place posts, such as those illustrated in Fig. 2. These posts are surmounted by metallic brushes, as shown, which are connected by means of 50 conductors with root-like wires buried in the ground. The posts may be independent of

each other or may be electrically connected, as indicated by the dotted line in Fig. 2. It is designed that the electrical waves be concentrated on a certain post, and in order 55 to accomplish this, the wave producer *c* should be placed the necessary distance from the principal focus of the parabolic reflector *b*. In order that the required focus may be at the required point, the distance is 60 computed by formulas well known to experts in this line.

It is to be understood that the apparatus is shifted from point to point so that the waves will be directed to and received by the 65 conductors carried by the different posts in the field, it being understood that the apparatus is first placed at or near the middle of the field, as indicated at *a* in Fig. 1.

From the foregoing description in connection with the accompanying drawing, it will be seen that I have invented a simple method 70 of intensifying the productive properties of the soil by Hertzian waves of high tension and great frequency, the generator of which 75 is useful in connection with a parabolic reflector *b* in order to concentrate the waves on the different posts. By this means, the atmospheric nitrogen or azote will combine with the mineral substances of the earth, 80 such as potash, soda and lime, transforming them into nitrates which are capable of being easily assimilated by the plants. While the post arrangement alone may be used for cultivation by concentrating the atmospheric 85 electricity on the field, it is clear that this phenomenon is intensified by the propagation of the waves before described.

Having thus described the invention, what 90 is claimed as new is:

1. The herein described process of treating fields for the purpose of hastening or intensifying their productive properties, which consists in placing in the field under treatment electrical conductors with terminals 95 buried in the ground, and in also placing in the field a producer of Hertzian waves of high tension and great frequency, and concentrating the waves upon the different conductors.

2. The herein described process of treating fields, which consists in placing on the 100

field under treatment conductors having their terminals buried in the ground, and in also placing upon the field a producer of electric waves of high tension and great frequency, in connection with a parabolic reflector designed to concentrate the waves upon any of the posts.

In testimony whereof I affix my signature in presence of two witnesses.

PORFIRIO DIAZ, HIJO. [L. S.]
